UNITED STATES PATENT OFFICE.

PETER FRANTZ, OF STERLING, ILLINOIS, ASSIGNOR TO FRANTZ MANUFACTURING CO.,
OF STERLING, ILLINOIS, A CORPORATION OF ILLINOIS.

CATCH.

1,201,714.

Specification of Letters Patent. Patented Oct. 17, 1916.

Application filed February 4, 1916. Serial No. 76,097.

To all whom it may concern:

Be it known that I, PETER FRANTZ, a citizen of the United States of America, and resident of Sterling, Whiteside county, Illinois, have invented a certain new and useful Improvement in Catches, of which the following is a specification.

My invention relates to catches or locking devices for use more particularly on doors and windows, and especially on basement windows.

The object of my invention is to provide an improved catch or locking device which can be cheaply manufactured from sheet metal, and having a handle which can be conveniently and effectively employed for pulling the door or window open, as well as for operating the device itself, and having also a cam action by which the door or window is not only tightly closed, but also forcibly opened a distance when the said handle of the device is rotated.

To this and other useful ends, my invention consists in matters hereinafter set forth and claimed.

In the accompanying drawings: Figure 1 is an inside view of a basement window provided with a catch or locking device embodying the principles of my invention. Fig. 2 is an enlarged front elevation of the said catch or locking device, showing the same in locking position. Fig. 3 is a vertical section on line 3—3 in Fig. 2. Fig. 4 is a perspective of the handle and rotary member of the said catch. Fig. 5 is a horizontal section on line 5—5 in Fig. 2.

As thus illustrated, the window A may be provided at its upper edge with hinges α of any suitable, known or approved character. Thus, the window swings inward in the usual and well-known manner. The catch or locking device for the lower edge of the said swinging sash comprises, as shown, three sheet metal pieces B, C and D, these three sections being held in place by screws 1 and 2, and by the pivot bolt 3, whereby the section C rotates about a horizontal axis formed by said bolt, which latter extends centrally through the upper section D which is secured flatwise to the inner surface of the swinging window sash. The section B has an upper portion b thereof pressed outward to form the stationary cam which extends obliquely to the plane of the body portion of the section B, the vertical edge 4 of

this cam being spaced a distance from the outer surface of the said section or plate. The section C has a disk-like central portion c which is perforated at its center to receive the bolt 3, and is also formed with a bail-shape handle 5 disposed, preferably, in the plane of the axis about which this section C rotates to lock and unlock the window. The plane of this handle 5 is, of course, a variable one, as it tilts about the said horizontal axis during the operation of the lock or catch. This section C has a cam portion 6 which engages the inner surface of the cam b to force the window very tightly into closed position. The said section C is also provided with another cam portion 7 which is adapted to engage the outer surface of the cam portion b , when the handle 5 is rotated into the position shown in dotted lines in Fig. 2, thereby to forcibly move the lower edge of the window sash outward a distance, so that the sash will be loosened at its lower edge by the mere unlocking of the catch. A notch 8 separates the adjacent edges of the cams 6 and 7, and the edge 4 enters this notch when the section C is rotated to the position shown in full lines in Figs. 1 and 2, whereby the cam 6 is behind the cam b in the manner shown more clearly in Figs. 3 and 5. The handle 5 can be used as a grip to pull the window open, if it does not open easily, so that this handle serves a double purpose. In other words, the said handle serves not only as a thumb-piece for twisting or turning the rotary section C of the catch, but is of such shape that it can thus be gripped to pull the window open. Thus, it will be seen that the three sections B, C and D are each made of one integral piece of sheet metal, and that the entire device can be manufactured very economically. The section D is perfectly flat, but the sections B and C are pressed or bent into the desired form, in the manner shown and described. Preferably, the opening 9 of the handle 5 is wide enough to receive the fingers of the hand by which the catch is unlocked, or at least one or more of the fingers, so that the operator can exert a strong pull if the window does not open easily.

I do not limit myself to the exact construction shown and described.

What I claim as my invention is:—
1. A catch for holding a movable element in stationary position, comprising a fixed

plate having a stationary cam portion, a rotary plate provided with a notch to receive said stationary cam portion and having inner and outer cam portions disposed in position to pass, respectively, inside and outside of said stationary cam portions, and a pivot for said rotary plate, two of said cam portions coöperating to tightly lock said member against movement, and one of these portions and the third portion coöperating to force said member from its stationary position.

2. A catch for holding a movable element in stationary position, comprising a fixed plate having a stationary cam portion, a rotary plate having inner and outer cam portions disposed in position to pass, respectively, inside and outside of said stationary cam portions, and a pivot for said rotary plate, two of said cam portions coöperating to tightly lock said member against movement, and one of these portions and the third portion coöperating to force said member from its stationary position, the two cam portions of the rotary plate having a notch between them to receive the stationary cam portion, one rotary cam engaging the inner surface of the fixed cam, the other rotary cam engaging the outer surface of the fixed cam, and both plates being formed from sheet metal.

3. A catch comprising a fixed plate having a stationary cam portion, a rotary plate having inner and outer cam portions disposed in position to pass, respectively, inside and outside of said stationary cam portions, when the rotary plate is turned in one direction and a pivot for said rotary plate, two of said cam portions coöperating when the rotary plate is turned in said direction, and one of these portions and the third portion coöperating when said rotary plate is turned in the opposite direction, the fixed plate being secured to a window frame, and said rotary plate being on the sash of said window, the first mentioned coöpera-

tion serving to tightly close the sash, and the other coöperation serving to forcibly open the sash a distance, said plates being formed entirely from sheet-metal, and said rotary plate having a notch to receive the stationary cam portion and a bail-shape handle to pull the sash open.

4. A catch for holding a movable element in stationary position, comprising a fixed plate having a stationary cam portion, a rotary plate having inner and outer cam portions disposed in position to pass, respectively, inside and outside of said stationary cam portions, and a pivot for said rotary plate, two of said cam portions coöperating to tightly lock said member against movement, and one of these portions and the third portion coöperating to force said member from its stationary position, the two cam portions of the rotary plate having a notch between them to receive the cam portion on the fixed plate, one rotary cam engaging the inner surface of the stationary cam, the other rotary cam engaging the outer surface of the stationary cam, and both plates being formed entirely from sheet metal, said rotary plate having a bail-shape handle extending outward therefrom and centrally of said pivot.

5. In a catch, a fixed plate having an outwardly displaced portion forming a stationary cam, a rotary member, means on said member to engage the inner surface of said cam when said member is partially rotated in one direction, and means on said member to engage the outer surface of said cam when said member is partially rotated in the opposite direction, said member having a notch to receive said cam.

Signed by me at Sterling, Illinois, this 29 day of Jan. 1916.

PETER FRANTZ.
